WILLIAM E. BROOKE, OF TRENTON, NEW JERSEY.

Letters Patent No. 83,248, dated October 20, 1868.

IMPROVEMENT IN SHUTTER AND BLIND-OPERATOR.

The Schedule referred to in these Letters Patent and making part of the same.

To all whom it may concern:

Be it known that I, WILLIAM E. BROOKE, of Trenton, in the county of Mercer, and State of New Jersey, have invented a new and improved Shutter and Blind-Operator; and I do hereby declare that the following is a full and exact description of the same, reference being had to the accompanying drawings, and to the letters of reference marked thereon.

Figure 1 represents a perspective view, showing the mode of operation.

Figure 2 represents a sectional view, showing a bar as attached to the shutter.

Figure 3 is a side attachment.

Similar letters of reference denote like parts.

The object of my device is to open, close, or fasten, and secure, at any desired angle, window-shutters or blinds, from the inner side, without raising the sash, by means of a worm-gear attached to the sill, or on the side of the window, thus dispensing with the use of shutter-bolts, rings, and turn-buckles.

To enable others to make use of my invention, I will proceed to describe the same.

A is a rod passing through or above the window-sill, under the lower sash, on the inner end of which rod is attached a knob or crank, B, for the purpose of bowing, opening, closing, or fastening the shutter, as required.

The outer end of crank B is provided with a worm-screw, C, supported by bearings, *a a*, which are secured to the sill. This worm-screw fits into a section of the pinion-wheel D, to which is attached the operating-bar E, curved at the outer end, and connected with slide

F by a pivot. The slide F is recessed, so as to fit closely on slide-bar G, which has a corresponding slot or dovetail, *b b*. The slide-bar G is permanently attached to the shutter or blind.

This device can be attached to the sill or the side of the window, and is applicable to shutters, blinds, or doors, and is a permanent and secure fastening for any desired angle of the shutter; and operated from the inner side, can be applied to any kind of window-frames without altering or damaging the wood-work.

It is attached to the side of the window by simply placing the worm-screw on the inner side of the wheel, and passing the rod A through the frame, as shown in fig. 3. The crank or knob by which the shutter or blind is operated thus becomes a curtain-holder on each side of the window.

Having thus fully described my invention,

What I claim as new, and desire to secure by Letters Patent, is—

The worm-gear C D, arm E, slide F, and slide-bar G, dovetail *b b*, or their equivalents, when constructed, arranged, and combined substantially as and for the purposes herein described.

In testimony whereof, I have signed my name to this specification in the presence of two subscribing witnesses.

WM. E. BROOKE.
